LIFTING DEVICE

Filed Dec. 24, 1926

Patented Nov. 27, 1928.

UNITED STATES PATENT OFFICE.

MICHAEL FALCO, OF CANONSBURG, PENNSYLVANIA.

LIFTING DEVICE.

Application filed December 24, 1926. Serial No. 156,774.

This invention refers to lifting devices and more in particular to a lifting device to be used in connection with a traveling crane for use in foundries, machine and assembly shops.

5 The primary object of this invention is to provide a lifting device having articulated lifting hooks which may be bent either inwardly or outwardly and which are adapted for distant-control.

10 Another object of this invention is to provide articulated lifting hooks which are adapted to engage the object to be lifted directly, that is without requiring the assistance of special floor-men whose duty it is to properly place the hooks on the object. A further object is to provide a lifting device having two sets of articulated lifting hooks which sets may be moved towards or away 15 from each other by the same man who operates the crane.

Additional features and advantages of this invention will be dealt with in the course of the following description considered in 20 connection with the accompanying drawing forming a part of this application and in which:

Fig. 1 is a side elevation of my lifting device.

30 Fig. 2 is a top plan view of Fig. 1.

Fig. 3 is a cross-sectional view taken on line 3—3 in Fig. 2, but with one of the articulated lifting elements broken away and with the cable-protecting plates removed from the articulated lifting-hook.

35 Fig. 4 is a fragmentary view, on an enlarged scale, of a cross-section taken substantially along line 4—4 in Fig. 1.

Fig. 5 is a fragmentary side elevation of 40 one of the articulated lifting hooks, also shown on an enlarged scale.

Fig. 6 is a cross-section through one of the cable-drums showing one method of securing to said drums the cables used for operating the articulated lifting hooks.

45 Fig. 7 is a plan-view of one of the component blanks used in building up each intermediate link of an articulated lifting hook.

Fig. 8 represents a longitudinal section 50 taken through an electromagnetic gear shifting device used in the present embodiment of this invention.

Fig. 9 is a general view showing diagrammatically the use of my invention in connection with a traveling crane.

55 One of the principal features of my in-

vention resides in the novel construction of the articulated lifting hooks. Reference being had to the drawing, each articulated lifting-hook comprises a plurality of intermediate link-members 1 which are connected together to form a chain terminating at the lower end with a grab-finger 2. As shown especially in Figs. 3, 5 and 7 each link member, in the present embodiment of my invention, is built up of several blanks 3 made of steel plate of proper thickness to suit the maximum lifting loads. Each blank comprises a body portion 4 having at one end a central and substantially semi-circular lug 5 and at the other end a semi-circular recess 6 adapted to accommodate therein a semi-circular lug of an adjacent link-member. The various link-members are hingedly connected together by means of pins 7 which engage suitable holes drilled in the lugs 5. In order to allow for sufficient relative arcuate movement between the connected links, the latter have all their corners bevelled off as indicated by the reference number 8.

80 Mounted for rotation on pins 9 and placed between the blanks of the link-members are the cable-guide rollers 10 arranged in two or more sets of three rollers each disposed symmetrically on each side of the longitudinal center-line of the links. Spacer strips 11 are placed between the blanks to provide the necessary room for said rollers and their cables 12.

85 The grab-finger 2 is connected to the lowermost link-member by means of a similar hinged connection as used between the links. This grab-finger is composed of blanks 13 the upper ends 14 of which are shaped to cooperate with the lowest link and the lower parts 90 15 of said blanks are substantially wedge-shaped, as plainly shown in the drawings. Adjacent the upper end of said grab-finger are placed the end-rollers 16 disposed in proper relation to cooperate with the rollers on the intermediate links. The rollers 16 are practically stationary and serve to bring the lower ends of the cables 12 as near the outer edges 95 of the grab-fingers as possible in order to obtain the greatest leverage for the cables, as 100 will be understood. The ends of the latter are fastened to the grab-finger in any suitable and desired manner, such as by pouring lead around them in pockets 17 formed in the grab-finger.

105 The various blanks and spacer strips used in building up the link-members and the grab-

5 fingers are securely held together by means of through bolts or rivets 18 as indicated in Fig. 5. To protect the cables 12, plates 19 and 20 may be fastened on the link-members and the 5 grab-fingers, respectively.

As stated before, the operating mechanism for the articulated lifting-hooks is adapted for distant control by the man operating the traveling crane. The mechanism shown in 10 the drawings consists of the following parts:—A frame member 21 comprising two parallel beams 22 securely mounted on the two end members 23 is suspended to the swivel-hook 24 of the traveling crane 25, (of 15 any suitable type) by means of cables 26 and hooks 27 (Fig. 9) engaging the apertures 28 provided in the upward extensions 29 of said two end-members.

Positioned midways of the beams 22 and 20 bolted thereto is a platform 30 upon which are mounted the electric motor 31, which provides the necessary power for operating the lifting hooks, and various other appliances to be described later. On both sides of this 25 platform are slidably mounted on the beams the two housings 32 and 33. As shown in Figs. 3 and 4 especially each housing has two machined openings or slices 34 which fit about the beams 22 and whereby said housings are properly guided for longitudinal 30 movement thereon. On the underside of said housings are fastened by means of bolts 35 the depending posts 36 the lower ends of which are suitably shaped and provided with 35 the proper pin and eye connections 37 for hingedly fastening the top ends of the uppermost link-members of the articulated lifting hooks. Upon these posts are secured the 40 guide-rollers 38 for the operating cables 12. The length of these posts depends on the local 45 conditions and on the clearance required between the underside of the frame-member 21 and the articulated lifting-hooks, the latter being made up of only as few links as required to suit requirements.

Each lifting-hook is provided with two sets 50 of operating cables 12 disposed on each side of the longitudinal axis of the lifting hook, each set of cables serving to bend the articulated hook in one direction only.

Each upper end of the cables pertaining 55 to the same lifting-hook is fastened in any desired manner, such as shown in Fig. 6, in a circumferential groove 39 cut in a drum 40. Therefore, each housing 32 or 33 has two such drums which are fastened on a common shaft 41 running in suitable bearings 42 and 43 provided in the walls 44 and 45 of said housing. These shafts and drums are actuated by the 60 motor 31 by means of the following mechanism:

Upon the inner end of the motor shaft 46 is fastened a worm 47 which meshes with a worm-gear 48 secured on a counter shaft, 65 49 rotatably mounted in bearing-supports 50

5 bolted to the platform 30. Secured on said counter-shaft by means of a feather key 51 is a shift-gear 52 which may be shifted into or out of engagement with another gear 53 secured on the center portion 54 of the worm-drive shaft 55 by means of a forked shift-lever 56 of usual design which is fulcrumed upon a vertical support 57 bolted to the platform 30. Said lever is actuated by an electromagnetic device 58 to be described herein- 70 after.

The worm-drive shaft 55 is rotatably mounted in bearings 59 provided in the upper part of the bearing-supports 50. This shaft has on each side of its central-portion 80 extensions 60 which are preferably square in cross-section and upon which are slidably mounted the drive-worms 61 which mesh with worm-gears 62 keyed or otherwise secured to the drum-shafts 41 and by which the drums 85 may be rotated. The ends of the worm-drive shafts have trunnions 63 rotatably supported in end bearings 64 which are mounted in the end-members 23.

The reason for making the shaft-extensions 90 60 square in cross-section is the fact that, as stated above, the housings are slidably mounted on the frame 21 and that the drive-worms must travel with said housing in order to maintain their engagement with the worm-gears 62. These square shaft extensions are supported by the housings 32 and 33 in the manner shown especially in Fig. 4. As shown therein, on each side of the housings are bolted the plates 65 having bearings 66 in which 95 are mounted for rotation the flanged bushings 67 having square central apertures adapted to slidably engage said shaft extensions. The articulated lifting-hooks, respectively the housings 32 and 33 are moved longitudinally on the frame 21 by the motor 31 in 100 the following manner: Suitably located on the platform 30 is a support 68 having a stub-shaft 69 upon which is held by means of a collar 70 the rotatably mounted spur gear 71 105 adapted to be engaged by the shift-gear 52. Said spur-gear meshes with another similar gear 72 secured upon a longitudinal spindle 73 positioned between the beams 22 and which is supported for rotation in bearings 74 secured to the end-members 23 and also in a bearing 75 fastened centrally on the underside of the platform 30. Upon this spindle are cut the left hand threads 76 and the right hand threads 77 which respectively engage 110 the accordingly threaded hubs 78 and 79 provided on the cross webs 80 cast integrally with the housings 32—33.

As will be understood, when the spindle 73 is rotated in either direction, the housings 115 will be moved in opposite directions along the frame 21 so that the spacing between the groups of lifting hooks may be varied to suit the dimensions of the object to be lifted.

Moreover, in order to facilitate the han- 120

dling of long but narrow objects, such as shafting, billets, rails, and so forth, it may be found desirable to dispose the lifting-hooks on one housing so that they may pass those on the other housing, to form substantially a closed loop underneath the lifted object. To this end, the lifting hooks on the housing 33 have been spaced sufficiently apart, in relation to the longitudinal axis of the frame 21 to enable said hooks to pass by the set of hooks on the housing 32. This is plainly indicated in Fig. 2 by the clearance 81. The latter may, of course, be enlarged arbitrarily to suit the requirement of the trade.

As stated, the shifting of the shift-gear 52 is effected by means of the electro-magnetic device detailed in Fig. 8. This device comprises a hollow cylindrical casing 82 supported on the legs 83. Centrally disposed within the casing are the two electrical coils 84 and 85 having a central sleeve 86 of sufficient bore to receive the slidable magnetic cores 87 and 88 which are secured in proper spaced relation upon a central push-rod 89 terminating at one end with a clevis 90 in which is hingedly secured by means of a pin and eye connection 91 the rear end of the shift-lever 56. The push-rod is guided for longitudinal reciprocating movement by the bearings 92 positioned in both end walls of the casing. The magnetic-cores are normally held in the neutral position shown in Fig. 8 by means of the two coil-springs 93 and 94 disposed around the push-rod and between said cores and the end-walls of the casing.

The solenoids 84 and 85 are electrically connected to an electrical power line 95 by means of the pole changer 96 and the three wires 97, 98 and 99 terminating respectively with the contacts 97^a, 98^a and 99^a.

When the pole changer is in the position shown in Fig. 8, no current will pass through either one of the solenoids and the push-rod will occupy a neutral position which causes the shift-lever to place the shift-gear 52 into neutral position halfway between the gears 53 and 71. If the pole-changer engages the contacts 97^a and 98^a, the electrical current will energize the solenoid 84 with the result that the core 87 is drawn into said solenoid and the shift-lever rotated so as to bring the shift-gear into engagement with the gear 53, whereby the worm-drive-shaft 55 may be rotated by the motor 31. On the other hand, if the pole-changer connects with the contacts 98^a and 99^a, the solenoid 85 will be energized and the shift-gear will be brought into mesh with the gear 71 to rotate the spindle 73 by the motor.

It is, of course, necessary that said motor be operated in either direction, and this could be effected, for instance, by placing in the circuit of the motor a reversing-switch of any desired type (not shown) now readily available in the trade. This reversing-switch as

well as the pole-changer 96 are installed in the operator's cab 100 of the crane 25 and connected to the motor and electro-magnet by flexible electric cables.

The bending of the articulated lifting-hooks requires a relatively very small winding of the cables 12, in fact less than a revolution of the cable-drums 61 will suffice. Such limited requirements predicate a close regulation in the operation of the electric motor and, to insure the proper stopping of the latter after the lifting-hooks have been properly bent, the motor is provided on the rear extension of its shaft 46 with a brake-pulley 101 which is acted upon by the electro-magnetically operated brake-shoes 102 of any desired commercial make. This brake would, of course, be electrically controlled from the crane-cap, or if desired, automatically, in a manner that will be readily conceived by persons versed in the art.

Substantially below the platform 30, an extra plate 103 is fastened to the beams 22 to increase their rigidity and to prevent any oil or grease from the gear 72 and the bearing 75 falling onto persons or merchandise below.

From the above description, the operation of my lifting-device will be readily understood and is as follows: It is customary in machine-shops and warehouses, etc. to lay the manufactured products not directly on the floor but on floor timbers, the purpose being to leave a certain clearance between said floor and products to facilitate the passing of the rope or chain-slings about the products, by means of which the latter may be hooked up to a crane. Assuming that an object 104 is to be lifted by means of my device, the crane-operator will first bring his crane and the frame 21 directly over the piece to be lifted. Then, by properly operating the pole-changer 96 and the reversing-switch (not shown) which controls the motor, he will spread the housings 32 and 33 sufficiently apart to enable the, now straight, lifting-hooks to come close to the sides of the piece under consideration. This done, the crane-man will again operate the pole-changer 96 in order to mechanically connect the motor with the worm-drive-shaft 55 and rotate the same in the proper direction to cause the lifting-hooks to bend under and engage the object to be lifted. The latter may then be raised to any desired height and transferred wherever wanted by means of the traveling crane 25, just as any other load.

It will be noted from the above that the handling of loads by means of my device may be performed rapidly and without requiring any slings, in most cases.

As will be understood, the size of the lifting-hooks and the number of cables 12 will be governed by the maximum load which a certain apparatus is designed for. The cables are kept in proper alignment for best re-

sults by passing them over and under the rollers 10 in the manner plainly indicated in Fig. 5 in particular.

While I have illustrated and described 5 herein the present and preferred embodiment of my invention, it may be found desirable after continued experience to make slight changes in the construction and arrangement of the details of my invention, and I intend to 10 include in this application all such variations as may be found profitable and as fall within the scope of the appended claims.

I claim:

1. In a lifting device of the character described, 15 a plurality of links; means for hingedly connecting the links end to end to form an articulated lifting member; a plu-

rality of rollers positioned within said links; cables guided by said rollers and engaging alternately the inner and outer periphery 20 thereof, and means for operating said cables.

2. In a lifting device of the character described, a plurality of links; means for hingedly connecting the links end to end to 25 form an articulated lifting member; a plurality of rollers positioned within said links; cables guided by said rollers and engaging alternately the inner and outer periphery thereof; means for operating said cables, and plates positioned on said links for protecting 30 said cables and rollers.

In testimony whereof I affix my signature.

MICHAEL FALCO.
